UNITED STATES PATENT OFFICE.

GEORGE B. GROVER, OF LYNN, MASSACHUSETTS, ASSIGNOR TO W. J. YOUNG MACHINERY COMPANY, OF LYNN, MASSACHUSETTS, A CORPORATION OF MASSACHUSETTS.

DIEING-OUT MACHINE.

1,063,871.

Specification of Letters Patent. Patented June 3, 1913.

Application filed April 1, 1912. Serial No. 687,797.

To all whom it may concern:

Be it known that I, GEORGE B. GROVER, a citizen of the United States, and resident of Lynn, in the county of Essex and State of Massachusetts, have invented certain new and useful Improvements in Dieing-Out Machines, of which the following is a specification.

This invention relates to a machine adapted to cut articles of determined form from sheet material, by means of a cutting tool or die having a cutting edge of the desired outline.

The particular machine illustrated in the accompanying drawings and particularly described in the following specification, which is one embodiment in practical form of my invention, is designed to cut lifts or pieces, to be used in the manufacture of boot and shoe heels, from sheets or strips of leather, leather board or like material, but the principles of the invention are equally applicable to cutting out other articles from the same or similar stock.

The principles in which the invention consists are discussed and explained in connection with the following detailed description of the particular form of means of carrying the invention into effect which I have shown for illustration herein.

In the drawings, Figure 1 represents the machine referred to, in front elevation, a part of the same being shown in section. Fig. 2 is a side elevation of the machine. Fig. 3 is a sectional elevation on line 3—3 of Fig. 2, showing a detail. Fig. 4 is a plan view of the guiding and supporting means for the stock. Fig. 5 is a cross section on line 5—5 of Fig. 4. Fig. 6 is an elevation on an enlarged scale of the stock-feeding means; the supporting table and cutting die being shown in section. Fig. 7 is a view similar to Fig. 6 showing the feeding means in a different position. Fig. 8 is a sectional view taken on a line 8—8 of Fig. 6. Fig. 9 is a sectional plan view of the cutting block. Fig. 10 is a sectional view elevation of the means for shifting the block between operations of the die. Fig. 11 is a sectional view on line 11—11 of Fig. 1. Fig. 12 is a plan view of the die and its holder.

Like reference characters indicate the same parts in all the views.

1 indicates a supporting frame on the upper part of which is a post or head 2 hav-

ing vertically alined separated bearings or sockets 3, 4 in which is fixed a pin 5 surrounded by a split sleeve 6 which is one end of a horizontally extending arm 7, the other end of which has a bearing 8 containing 60 a rotatably a shaft or post 9 to which a cutting block 10 is secured. This block constitutes the bed or abutment which sustains the stock or material against the thrust of the die when the heel lifts or other articles 65 are being cut. It is preferably made of wood, but may be of any other material having the essential qualities of firmly supporting the material and of not injuring the cutting edge of the die. It is cylindrical in 70 form and is secured coaxially with the post 9, the securing means being conveniently clamp-screws 11 which pass through lugs 12 embracing the block at one end and carried by a plate 13 which is fastened 75 by bolts 14 to a flange 15 in the lower end of the post 9. Rising from the arm 8 and overlying the post 9 is a goose-neck 16 having an aperture coaxial with the post 9 through which extends a screw 17 which 80 has a threaded engagement with the post as shown in Fig. 1. A hand wheel 18 is secured to the end of the screw and rests on the upper side of the goose-neck, being rotatable thereon as the screw is fully rotated within the goose-neck. The post 9 is also freely rotatable within the bearing 8, so that it may be turned more or less from time to time as will be hereinafter described. A block 19 which fits the threads 90 of the screw 17 is set into a passage in the side of post 9 and is pressed against the screw by a spring 20 which abuts against a screw 21 threaded into the outer end of the passage. The function of this block is to 95 act as a friction device preventing relative rotation of the post and screw when the block is indexed as hereinafter described, but permitting the screw to be turned relatively to the post for adjusting the height 100 of the block.

The cutting element is a die 22 beneath the block, of which the cutting edge extends toward the block and is moved against and away from the same periodically by suitable 105 mechanism. The die here shown is tubular and is adjustably mounted upon a plate 23 between clamping set screws 24, 25 threaded through lugs 26 on said plate. The plate in turn is removably supported upon the 110

flat top 27 of a carriage 28 which reciprocates vertically and has guiding flanges 29 contained in guide ways 30, formed on the front part of the machine frame and being of any usual or desired form. The top part 27 of the carriage has ribs 31 at opposite edges between which the plate 23 fits, and on which are retaining strips 32 overlying the edges of the plate. Thus the die-holding plate is removable from the carriage, and plates equipped with dies of different sizes and forms may be readily substituted for one another. A locking pin 33 passes through one of the ribs 31 into a hole in the plate 23 and is retained therein by a spring 34 which is a strip of spring steel fastened at one end to the rib 31 and engaged near its free end with the pin. This pin insures retention of the die-holding plate upon the carriage and placing of any of such plate in the proper position. As shown in Fig. 11, both the die supporting plate and the top plate of the carriage are apertured in line with the hollow interior of the die to allow the pieces cut by the die to fall into a receptacle. The carriage itself is so made as to allow the pieces to fall away without obstruction, its central part 35 between the cut flanges 29 being inclined backward. Stiffening webs 36 extending forwardly are provided on each side of the inclined central part.

The operating means by which the die carriage is reciprocated consist of a lever 35 pivoted upon a stud 38 between lugs 39 of the frame, having a forked end 40 embracing a stud 41 on a pin 42 between lugs 43 of the carriage, a connecting rod 44 (Fig. 2) and a crank pin 45 contained in a box on the end of the connecting rod and carried by a crank 46 on a main driving shaft 47. The latter is equipped with belt driven pulleys 48 and 49, one of which is tight and the other loose.

The stock from which lifts are to be cut, shown in Figs. 5, 6, and 7, and designated by the numeral 50, is placed upon a table 51 and fed beneath the block 10 close to the under side thereof. On the table is a guide 52 (see Fig. 4) which engages one edge of the stock and positions the same relatively to the die. Preferably guide 52 is adjustable so that the edge of the stock may be brought more or less close to the periphery of the die, and for this purpose it is mounted pivotally upon a stud 53 rising from the table, and is adjusted by means of a screw 54 held rotatably in the lug 55 on the table and threaded into a block 56, which is pivotally mounted upon the guide. A head 57 is secured on the screw to enable the same to be easily turned between the thumb and finger of the operator.

The particular machine illustrated is designed to act upon strips of stock having a

width approximately equal to the greater dimension or length of the article to be cut therefrom, although the invention is not limited in all its aspects to this feature. Therefore I provide a complementary guiding means adapted to engage the opposite edge of the strip from that engaged by guide 52, and to hold the strip in contact with said guide, such means consisting of arms 58 and 59 pivoted at 60 and 61, respectively, upon a plate 62 supported on the table. The arms have alined projecting portions adapted to engage the edge of the strip, which are pressed toward the latter by springs 63 and 64 arranged as shown in Fig. 4 or in equivalent manner. Stops 65 and 66 are provided to limit the amount by which these springs may move the guiding arms. The plate 62 is adjustable on the table and has slots 67 extending in the direction of adjustment through which clamping screws 68 extend, such screws being threaded into the table and having heads adapted to bind the plate to the table in any well known manner. An adjusting screw 69 having a head 70 is journaled in a bearing 71 in the table and threaded through a part 72 of the plate. By this means the guide arms 58 and 59 may be adjusted to accommodate strips of various widths, and the yielding mode of mounting the arms adapts the latter to accommodate themselves to irregularities in the width of the strips. On the guide 52 is mounted a plate 73 of which one end extends under the block and has a lateral projection 74 extending across more than the entire width of the strip. The guide arms 58 and 59 carry, respectively, plates 75 and 76 which overlie the edge of the strip engaged with said arms. These strips cause the advancing end of the strip to pass under the block without interfering therewith and also prevent any part of the strip from buckling and escaping from between the guiding elements. The ends of the plates under which the strip first passes are preferably bent up more or less to insure that the strips will pass readily beneath them, while the tip portion 77 of the plate 75 is bent down to insure that the advancing end of the strip will pass under the part 74 of plate 73. The plates 75 and 76 are preferably made integral with the arms 58 and 59, respectively, such parts being most economically made as castings.

The feeding means consists of a pointed finger 78 carried by an arm 79 on a shaft 80 which is held in a bearing 81 and is moved oscillatively by a cam 82 having an axially offset cam face 83, as shown in Fig. 1. The cam element acts on a roll carried by an arm 84 (see Fig. 2) affixed to a telescopic shaft consisting of a key-coupled rod 85 and sleeve 86, which latter is connected with the shaft 80 by a universal joint 87. The motion pro-

duced thereby swings the arm 79 and finger 78 from right to left as viewed in Figs. 1, 6, and 7 causing the point of the finger to enter the stock and advance it. Return movement of the finger into position for a further feeding is produced when permitted by the cam by a spring 88 connected to a finger 89 on the hub of the arm 79, and to a fixed part of the machine.

- 10 Adjustment of the finger to secure different extents of feeding movement, but without altering the position of the finger at the end of feeding movement, however great the extent of such movement may be, is 15 accomplished by mounting the finger 78 movably upon the arm 79. This finger is journaled upon a sleeve 90, shown in Fig. 8, having a flange or head 91 and surrounding a pin 92 which passes through a slot 93 in 20 the arm 79 and has a head 94 on the opposite side of the arm from flange 91. A nut 95 is screwed on the pin 92 and serves to force the flange 91 and head 94 toward one another or to release them, so that the pivot 25 may be placed and secured at any point within the limits of slot 93. Surrounding the sleeve 90 is a sleeve 96 having an external boss 97 entered by an adjusting screw 98 which has a bearing in a block 99 pivoted 30 at 100 in a wing 101 of the arm 79. As the screw extends nearly parallel with the slot 93, it serves to adjust the feeding finger pivot along such slot, while the pivotal mounting of the block 99 allows the screw 35 to swing as much as may be necessary to permit the pivot to follow the curvature of slot 93. As both the nut 97 and the finger 78 are able to swing on the pivot sleeve 90, adjustment is freely permitted. The finger 40 is held up to the work by a spring 102 coiled about the sleeve 96 and secured thereto, one end being hooked under the finger. I prefer to make the point 78^a of the finger separable from the body of the finger in order that it 45 may be removed for sharpening and replaced without the bother of removing the entire finger and of disassembling all the parts associated with the finger in order to do so. Accordingly the point is a separate piece 50 which is held removably upon the body of the finger by a steady pin 103 and a screw 104. I have shown associated with the finger a means for preventing the point from penetrating too far into the stock, such means 55 comprising an arm 105 adjustably mounted on the finger by means of a screw 106 passing into the finger through a slot 107 in the arm. Such arm carries on its outer end a roll 108 designed to run on the under side 60 of the table beside a slot 109 in the latter through which the finger point projects to engage the work. This arm is not an important part of the invention and may be omitted without detriment. In one form of 65 the invention which I have put into practice

the arm is omitted and the finger allowed to enter the stock as far as it will. When no stock is present the finger makes contact with a hardened steel strip 110 on the under side of plate 73.

70 In order that the finger may be so adjusted as to vary the extent of feeding at which feeding ceases, I make the slot 93 on a curve of which the radius is equal to the distance between the point of the finger and the pivot thereof, and the position of the groove in the arm 79 is such that when the arm and finger are at the end of the feeding movement the center of curvature of the slot is at the point of the finger. Thus, when the 80 pivot of the finger is adjusted in slot 93, no change of this position of the finger point occurs, however great the adjustment may be, but in the other limit of the feeding, which is the position shown in Fig. 7, a 85 great change may be made in the position of the finger point. Thus it may be said that the entire adjustment of the finger occurs at one end of its movement, that is, the commencement of the movement.

90 Adjacent to the feed finger and preferably arranged on opposite sides thereof are two or more fingers 111 mounted upon pivot pins 112 supported from the table beneath the latter, which fingers are actuated by springs 95 113 so as to press the sheet or strip of stock against the plate 73 at points very close to the die. These fingers become useful when the end of the stock approaches the die, as they hold the last bit of stock in place 100 against the block and prevent the ends of the strips from dropping and being wasted.

105 The block is movable so that every part of its surface may be brought over the die to prevent uneven cutting away. Movement for this purpose is produced in part automatically and in part by manual adjustment. The automatic movement is a rotary one and may be called for convenience an "indexing" movement. It is produced by 110 a disk cam 114, the shape of which is shown in Fig. 2, on the shaft 47 which acts upon a roll 115 carried by a lever 116 pivoted on a stud 117 and having an arm 118 connected by a link 119 with a pawl carrier 120 arranged to travel upon the periphery of the plate 13, previously mentioned, and embracing a circular line of ratchet teeth 121 on said plate. The pawl carrier has two 115 pawls 122 and 123 separated by a distance which is a multiple of half the spacing of the teeth 121 and which is adapted to coact with these teeth. The amount of movement given to the pawl carrier is governed by a 120 stop screw 124 carried by the lever 113 and adjustable thereon. This stop screw limits the amount by which the roll 115 follows the cam 114 to any desired extent and thereby enables the indexing movement to be 125 carried from a minimum of half the tooth 130

spacing to a maximum of several times this amount. This indexing movement presents a fresh surface of the block to the die at each cut until one rotation has been completed. The other adjustment of the block is occasioned by swinging the arm 7 about the stud 5 to cause the die to act against another circular zone of the block's surface. The hub 6 of the arm 7 is split and is provided with take-up screws 125 to draw the parts together, whereby the arm may be secured by clamping after each adjustment.

It will be noted that the pawl carrier 120 travels in a curved path in a horizontal plane while arm 118 moves in a vertical plane. To permit these movements, the link or connecting rod is engaged with the arm 118 by a horizontal pivot 126, a yoke 126^a, and a vertical pivot 126^b, while the connection between the link and pawl carrier is made through a yoke 127 having a vertical stud 128 journaled in the end of the link 119 and having lugs which straddle the pawl carrier and are pivoted thereto by horizontal studs 129.

The table and the feeding means are all adjustable in unison vertically to a limited extent and are all carried by a slide 130, the table being secured upon a plate 131 on the top of the slide, and the shaft 80 upon which the feeding finger is supported being contained in a bearing sleeve 81 which forms a part of the slide. The latter is removably secured to the machine frame by bolts 132 passing into the body of the frame through slots 133 in the slide and having clamping heads overlying the edges of the slots. The slide is guided by one edge of an angle piece 134 which is secured to the body part of the machine frame and forms a portion thereof. When the clamping bolts 132 are released the slide and all parts carried thereby may be raised by means of a hand lever 135 pivoted at 136 and connected with the slide by a link 137. It is for the purpose of permitting this adjustment that the telescopic shaft drive and flexible coupling are provided for the shaft 181. The bearing 138 which supports the telescopic shaft has a swivel mounting at 139 upon the machine frame, thereby, and on account of the telescopic construction and the universal joint, permitting shaft 80 to be raised and lowered. The feed may be made inoperative by a latch 140 hung on a pivot 141 at the side of the frame and adapted to engage a tooth 142 on a collar 143 which is secured to the sleeve 86 of the telescopic driving shaft. By lifting a handle 144 on the arm 79 the shaft and the collar 143 may be turned far enough in the direction of feeding to cause the latch to engage the tooth 141. These parts then hold the finger somewhat beyond the most advanced position given it by the cam 82, whence the cam may rotate idly

without imparting any movement to the finger.

I desire to have it understood that I do not limit my invention to the particular machine or the details of construction thereof herein illustrated and particularly described, and that in its broader aspects the invention is limited only to the principles of construction and operation of which the construction shown herein is one exemplification. All changes and modifications coming within the language of the annexed claims are included under my invention. It is within the scope of the invention to make the dies double and to have the strips or sheets of stock sufficiently wide to overlie the double die, whereby two complete lifts or other articles may be cut at one operation. The parts of the double die are the reverse of one another, so that a pair of similar but opposite articles may be cut at one operation.

A feature of great importance in the present invention is that the block is above the die and is relatively stationary, while the die in cutting moves back and forth across the line in which the stock is fed. As a result of this arrangement it frees itself of the stock, and the scraps do not rest upon or adhere to the block in such a way as to interfere with subsequent operations. The scrap which passes beyond the die falls into an inclined guide way 150 by which it is led away to one side. Some of the scrap falls beside the die, and in order to prevent it from dropping into the receptacle placed beneath the carriage to receive complete articles, I provide deflector plates 151 and 152, the former of these is fastened to the front edge of the die-holding plate 23, and rises on an upward and rearward slant, having a hole to receive the die. The latter is secured under the forward edge of the carriage top plate and extends forwardly therefrom on an incline. These deflectors are shown only in Fig. 11, being omitted from Figs. 1 and 2 for the sake of clearness. The edged cutting die and coöperating cutting members may be considered as typical of any two coöperating or complementary cutting members, and therefore I do not limit my invention or the scope of all of my claims to the particular type of die and cutting block here shown. Any complementary cutting members capable of forming articles in the nature of heel lifts and the like from sheets of leather, leather board, or equivalent material are within the intended scope of the broader claims hereinafter following.

I claim;

1. A machine for cutting articles from sheet material comprising a cutting block, an edged die mounted with its cutting edge directed toward the block and located beneath the latter so that scraps of the mate-

rial left after cutting may fall away therefrom, a die carriage, mechanism for reciprocating said carriage and die toward and from the under side of the block, and feeding means located at the side of the block from which the material acted upon advances arranged to cause such material to travel in a path below and close to the under face of the block.

5 2. In a machine of the character described, a die consisting of a tubular member having a cutting edge on one end, a holder consisting of a plate upon which the end of the die opposite to its cutting edge bears, and clamping means for securing the die thereto; a carriage having a top plate upon which said die holder rests, and having guiding ribs or flanges, guide ways in which said ribs are slidably contained, mechanism 10 for moving said carriage, and a cutting block toward and against which the die is forced in its operative movements, the die holder and the plate of the carriage having apertures in line with the material of the die to permit escape of the pieces cut by the die.

15 3. A dieing out machine, comprising in combination, a cutting die and a block against which the die acts, a feeding means for the material acted upon comprising a 20 guide for directing the material between the die and block, a feeding finger movably mounted at the side of the die from which the material advances, projecting toward the die from its point of support, and arranged to travel toward and from the die, and means for reciprocating said finger across the face of the block substantially up to the point at which the die strikes the 25 block, the finger being arranged to engage the stock.

30 4. A machine for cutting strips of sheet material into pieces of which one of the dimensions is approximately equal to the width of the strips, comprising in combination, a cutting die, a block arranged to support the strip against the thrust of the die, means for moving the die toward and from one face of the block, a table for supporting 35 the strip, a plate extending from said table partly across and close to the said face of the block, a feeding finger having a point, located at the opposite side of the strip from said plate with its point extending 40 toward the die, and means for moving said finger toward and from the line of the die and causing its point to enter the stock and push the same across the die.

45 5. In a machine for the purpose stated, in combination with a die having a cutting edge at its upper end, a cutting block located above said die with its under surface arranged to sustain the material acted upon against the thrust of the die, a plate for 50 guiding the material acted upon extending

partly across and close to the acting face of said block, a rock shaft, an arm secured to said rock shaft and oscillated thereby, and a feed finger pivotally connected to said arm beneath said plate and having a portion extending from its pivot connection toward the plate and toward the die arranged to engage and propel the material when the finger is moved by the arm in one direction.

55 6. In a machine for the purpose stated, in combination with the coöperating cutter and cutting block, a table having provisions for guiding the material acted upon in a plane close to the acting face of said block, a rock shaft, an arm secured to said rock shaft and oscillated thereby, and a feed finger pivotally connected to said arm and having a portion arranged to engage and propel the material when the finger is moved by the arm in one direction, the pivot of the 60 finger being adjustable on the arm along a curved line of which the radius is equal to the distance of the finger point from its pivot, and so located that its center of curvature coincides with the finger point when the arm is at the end of its feeding movement.

65 7. A machine of the character described, comprising a cutting block, a die movable toward and from a surface of the block, a 70 guide for the material acted upon, a feed finger having a point so arranged as to enter the material when moved in the feeding direction, and an oscillating arm located at the side of the die from which the material advances to which the finger is pivoted and from which the finger projects toward the die, arranged to swing in such direction as to give the arm alternating feed and return movements, and means for connecting the 75 finger to the arm at various points equidistant from the point at which the finger engages the material, when the arm is at the end of the feed movement, whereby the extent of feeding may be varied without 80 changing the point at which the feed ends.

8. A cutting machine comprising a suspended cutting block, a cutting die arranged to reciprocate toward and from the under surface of said block, mechanism for so reciprocating the die, a guide for the material acted upon arranged to direct the same beneath and close to the under side of the block, a feeding means including an oscillating arm and a feed finger pivoted to said arm, the finger having a portion adapted to engage the under side of the material and movable back and forth beneath the block in the direction in which the material is guided, and a support for the material yieldingly actuated to press the same toward the block at a point close to the die.

9. In a machine of the character described, the combination with a cutting die movable approximately vertically and hav-

ing a cutting edge on its upper end, a block 5 mounted above the die and arranged to support the material acted upon against the thrust of the die, by its under surface, a support for the material located beneath and close to the acting face of the block, a reciprocating feed finger beneath the material arranged to travel toward and from the die, its movement toward the same terminating 10 at a point close to the latter, and members on each side of said feed finger yieldingly pressed toward the block at points close to the die for supporting the last bit of a piece of the material in position to be acted upon 15 by the die.

10. In a machine of the character described, a feeding device comprising an oscillatively mounted arm, a pivot stud secured to said arm, a feed finger pivoted upon 20 said stud, a nut also pivoted upon said stud, an adjusting screw connected to said arm and engaged with said nut for shifting the same and the pivot stud upon the arm, the latter having a guiding slot, and clamping 25 means for securing the pivot at different points within the limits of the slot.

11. In a machine of the character described, a feeding device comprising an oscillatively mounted arm, a pivot stud mounted 30 on said arm, a feed finger pivoted upon said stud and provisions for placing said stud at positions more or less remote from the axis of said arm.

12. In a machine of the character described, 35 a feeding device comprising an oscillatively mounted arm having a guideway, a pivot stud mounted in said guideway and thereby secured to said arm, being adjustable along the guideway, and a feed finger pivoted 40 upon said stud, said guideway being curved on an arc of which the radius is substantially equal to the distance of the feed finger point from the said stud, and the location of the guideway is such that its center of 45 curvature coincides with the point of the finger when the feeding device is at the end of its feeding stroke.

13. In a machine of the character described, 50 a feeding device comprising an oscillatively mounted arm, a pivot stud adjustably secured upon said arm, a feed finger pivotally mounted upon said stud, and an adjusting screw mounted rotatably on said arm and having threaded engagement with 55 said nut for shifting the same and, with it, the stud and feed finger upon the arm.

14. In a machine of the character described, 60 a feeding device comprising a vibrating arm, having a guideway, a stud mounted in said guideway and adjustable therein, a feed finger pivotally mounted on said stud, and an adjusting screw rotatably carried by said arm and having a threaded engagement with a portion of said stud, said

screw being arranged to shift the stud along 65 the guideway.

15. A machine for cutting pieces of particular shape from strips which have approximately the same width as one of the dimensions of the cut piece, comprising a die 70 having a generally annular cutting edge, a cutting block for sustaining the strip against the thrust of the die, said block being above the die, and the die being open and arranged to cut upwardly against the under face of 75 the block, whereby the pieces and scraps are cleared away by gravity, and means for feeding the strips between the block and die, said means being located, when at the end of the feeding movement, so close to the die as 80 to engage the smallest remaining end of the strip which is large enough to furnish a complete piece.

16. A machine for cutting pieces of particular shape from strips which have approximately the same width as one of the dimensions of the cut piece, comprising a die 85 having a generally annular cutting edge, a cutting block for sustaining the strip against the thrust of the die, said block being above 90 the die, and the die being open and arranged to cut upwardly against the under face of the block, whereby the pieces and scraps are cleared away by gravity, and means for feeding the strips between the block and die, 95 said means being located, when at the end of the feeding movement, so close to the die as to engage the smallest remaining end of the strip which is large enough to furnish a complete piece and said feeding means being 100 adjustable to vary the extent of its feed movement, while causing the point at which such feed movement ceases to remain constant, whatever the adjustment.

17. A machine for cutting pieces of particular shape from strips which have approximately the same width as one of the dimensions of the cut piece, comprising a die having a generally annular cutting edge, 105 a cutting block for sustaining the strip 110 against the thrust of the die, said block being above the die, and the die being open and arranged to cut upwardly against the under face of the block, whereby the pieces and scraps are cleared away by gravity, 115 means for feeding the strips between the block and die, said means being located, when at the end of the feeding movement, so close to the die as to engage the smallest remaining end of the strip which is large 120 enough to furnish a complete piece and resilient supporting means yieldingly pressed toward the active face of the block at a point sufficiently close to the die to retain such remaining end in proper position to be acted 125 on by the die.

18. In a machine of the character described, the combination with an over hung

- block, a cutting die arranged to act against the under surface of said block, a table for supporting the material acted upon arranged to direct the same close to the under surface 5 of the block, a guide secured upon the table engaging one of the edges of the material, a movably mounted guide member engaging the opposite edge of the table and yieldingly pressed against the same, and plates secured 10 upon said guides overlying the material to retain the same between the guides.
19. In a machine of the character described, a table for supporting the material to be acted upon, a relatively fixed guide for 15 engaging one edge of the material, a movable guide for engaging the opposite edge of the material, means yieldingly pressing said movable guide toward the relatively fixed guide, and means associated with said guides 20 overlying the material to retain the same between the guides.
20. In a machine of the character described a table for supporting the material acted upon, a relatively fixed guide for engaging one edge of the material, and movable guides engaging the opposite edge of the material at separated points, said movable guides being yieldingly pressed toward the material and adapted to yield independently. 25
21. In a machine of the character de- 30
- scribed, a feed table for supporting the material acted upon, a relatively fixed guide on said table adapted to engage one edge of the material, a slide relatively adjustable on the 35 table and movable toward and from said guide, and independently movable guide members mounted upon said slide for engaging the other edge of the material, said guide members being yieldingly pressed toward the relatively fixed guide. 40
22. A dieing out machine comprising in combination, a die, a thrust block, above the die, means for moving the die upwardly against the block, and back, a feed member 45 arranged to advance the material acted upon between the die and block and yielding means pressing the material upwardly toward the block.
23. A dieing out machine comprising a 50 die, a thrust member by which the material is supported against the pressure of the die, feeding means, and a yielding presser arranged to act against the material to assist in holding it in place between the die and 55 thrust member.

In testimony whereof I have affixed my signature, in presence of two witnesses.

GEORGE B. GROVER.
